United States Patent Office

Des. 178,863
Patented Oct. 2, 1956

178,863

FOOT MEASURING DEVICE

Charles F. Brannock, Syracuse, N. Y.

Application October 3, 1955, Serial No. 38,193

Term of patent 14 years

(Cl. D52—1)

Fig. 1

Fig. 2

Fig. 3

Fig. 4

Figure 1 is a top plan view of a foot measuring device embodying my new design.

Figure 2 is a side elevational view.

Figure 3 is a lengthwise sectional view.

Figure 4 is a transverse sectional view taken on line 4-4, Figure 1.

I claim:

The ornamental design for a foot measuring device, as shown.
